UNITED STATES PATENT OFFICE.

ROBERT NEIL WILLIAMS, OF LONDON, ENGLAND, ASSIGNOR TO POWERS ACCOUNTING MACHINE COMPANY, OF NEW YORK, N. Y., A CORPORATION OF DELAWARE.

PERFORATING-MACHINE.

1 311 744.

Specification of Letters Patent. Patented July 29, 1919.

Application filed November 10, 1915. Serial No. 60,632.

To all whom it may concern:

Be it known that I, ROBERT NEIL WILLIAMS, a citizen of the United States of America, residing in London, England, have invented certain new and useful Improvements in Perforating Machines, of which the following is a specification.

This invention relates to improvements in perforating machines designed for use in the perforation of cards for tabulating and like machines, which cards are divided into a number of fields, such fields representing the various data or matters concerned.

In use, the perforated cards are passed through a tabulating machine with which are associated counters, whereby the value represented by the various perforations in each field in successive cards are added together.

It is sometimes found desirable, however, to record not only the cumulative value of the various perforations in the respective fields in successive cards, but also the number of times that any one field in a series of cards has been perforated.

The present invention has for its object to provide means whereby the card in its passage through the perforating machine, shall, in addition to the perforations in the respective fields, receive other perforations which indicate whether or not the cards receive a perforation in any one field.

The present invention has for its further object to provide for the automatic formation of one or more perforations indicative of any one or more facts which are consequent upon any one or more of a series of other facts, which are recorded by the operator. Upon the other hand, the fact to be recorded may simply be the number of times that the cards are provided with a perforation or perforations in any one field. In other words, each time a perforation or perforations is or are made in any one field or fields, one or more perforations is or are automatically made in the card so that as they pass through the counting machine the total of all the fields receiving a perforation is secured.

Broadly defined, the means whereby the desired object is attained comprises a movable member or members which is or are so associated with the selective mechanism whereby the punches are set by the operator to punch the card that when the said mecha-

nism is set any or all of the movable members as the case may be are caused to assume a position such as to cause the formation of the desired perforation or perforations upon the occurrence of the perforation produced by the operator.

In order that the invention may be the better understood drawings are appended in which:

Fig. 1 is a side elevation, partly in section, of a perforating mechanism, constructed in accordance with the present improvement;

Fig. 2 is a fragmentary side elevation of the mechanism shown in Fig. 1;

Fig. 3 is a fragmentary top plan view of the mechanism shown in Fig. 1;

Fig. 4 is a fragmentary vertical sectional view taken on the line 4—4 of Fig. 3;

Fig. 5, is a vertical sectional view taken on the line 5—5 of Fig. 4.

In the accompanying drawings the invention is illustrated as applied to the type of machines forming the subject of U. S. Patents 1,086,397 and 682,197, and in which a series of settable slides are employed controlled by keyslides, the settable slides being provided with a projection which, when the slides are set are each brought over the head of one of a series of punches, which is thereupon held rigid against the advance of a die plate. The card is placed between the punches and the die plate so that when said plate is advanced those punches over which the aforesaid projections have been located are caused to perforate the card.

Referring now to the accompanying drawings in detail, in which like reference characters designate similar parts throughout the several figures, *a* (Fig. 1) indicates the die plate, *b* a guide plate for the punches *c*, and *d* indicates the slides controlled by keyslides *d* through the medium of levers *d*, both of said elements being operatively mounted in a frame work *g* as is clearly shown and described in said U. S. Patent 1,086,397. The slides *d* are provided with projections such as *f*. *g* indicates a plate secured by means of screws *g*, to the frame of the main machine *g*. The plate *g* is provided with a number of rectangular perforations which form guides for rectangularly shaped plugs *h*, the lower ends of said plugs being provided with spindles *i* upon which are mounted rollers *j* designed to

engage the upper surfaces of the aforesaid slides d . The cards which are fed into the machine similar to the card feed described in said U. S. Patent 1,086,397, are divided into fields, each field containing a certain number of columns in accordance with the value represented by the perforations. Thus where the field represents pounds, shillings and pence, there will be three slides d . For each column in the field there will be a corresponding number of slides, and consequently a corresponding number of rollers 5 will be provided upon the particular plug 3 representing the field, it being understood that in the case illustrated it is simply desired to record upon a separate field on the card, which of the main fields have been punched. The field just referred to, for purposes of identification, is hereafter referred to as a "field key". The slides d are recessed at d^1 , the rollers 5 normally lying in the recesses as shown, and the front walls of the recesses are each provided with an inclined surface d^2 so that as the slides d are pulled forward by means of the levers d^3 , the rollers 5 running up the said incline d^2 , cause the plugs 3 to be raised. Pivotally mounted upon blocks 6 secured by screws 7 to the upper surface of plate 1, are bell crank levers 8, the horizontal member of each of which lies just above the upper end of one of the perforations in plate 1 and one of the blocks 3. Slidably mounted in guides 9 and 9^1 , secured by screws to the upper surface of plate 1 are horizontal rods 10 and 10^1 of rectangular cross sectional outline and which rods at their outer ends are disposed adjacent a number of perforations 12, arranged transversely of plate 1 and forming guides for pins 11 reciprocatably mounted, which pins rest upon the heads of the punches c . The length of the pins 11 is such that their upper ends normally are flush with the upper surface of plate 1. Consequently, when the rods 10 are advanced in the direction of the arrow, their ends more or less cover the ends of pins 11, which are thereupon prevented from rising as the die plate a is forced up, and the punches perforate the card. In the present instance there are 10 fields upon the card, of which it is desired to obtain a record in the field key, and therefore a corresponding number of punches c , and pins 11 are provided, the said punches from the front to the back of plate 1 representing the corresponding fields and being so numbered on the drawings. Obviously, the arrangement of the perforations in the field key may be raised as may be found convenient or desirable. In the present instance the main fields 2 and 3 contain two columns only, and of the fields 4 and 5 a record is required in only one of the said fields at one time. Provision is therefore made whereby the operator may select either of the desired fields 4 and 5; which is to be represented in the field key. To this end there is provided a lever 13 slidably and pivotally mounted upon the upper surface of plate 1 by means of the slot 14 therein through which passes a screw 15. A rod 15 ^{1} attached to the lever 13 connects same with a hand actuated lever 16 carried by a bracket 17, mounted upon the front of the framework of the machine. The automatic operation of the lever 13 is secured by means of the rod 10 ^{4} which is recessed at 10 ^{5} for the passage of the said lever 13, the edges of the recess engaging the sides of the lever so that when the rod 10 ^{4} is operated the lever will be swung upon its pivot 15 and according to its position its curved outer end 13 ^{1} will cover either the perforation 4 or 5 in the plate 1. The rods 10 are returned to their normal position by means of springs 18. In order to keep the arrangement within the capacity of plate 1, the rods for the perforations 8 and 9 instead of moving directly over their respective perforations operate levers whereby the covering of the said perforation is effected. Thus in the case of the means for covering the perforation 8, there is provided a lever 19 pivotally mounted at 19 ^{1} to the upper surface of the plate 1, said lever projecting in a slot 19 ^{2} in the rod 10 ^{4} which rod is slotted sufficiently to enable the aforesaid lever 13 to move freely without affecting the said rod 10 ^{4} . In the case of the perforation 9 there is provided a lever 20 pivotally mounted upon a block 21, one end of the lever being disposed directly over the plug 3 ^{1} . The opposite end of lever 20 engages a second lever 22 having a pivotal connection at 23 with a rod 10 ^{5} moving in guides 24, 25 secured to the upper surface of plate 1, the latter guide 25 also having slots for the aforementioned rods 10 ^{4} and the rod 10 ^{4} for actuating the lever covering the perforations 4 and 5.

From the above it will be seen that the perforations marked "0," "1," "2" and "3" are covered by the reciprocation of the rods 10; the perforations marked "4" and "5" are covered by the rocking of the lever 13 about its pivot; the perforations "6" and "7" are covered by the reciprocation of rods 10 ^{4} ; the perforation "8" is covered by a rocking of the arm 19; and the perforation "9" is covered by a reciprocation of the rod 10 ^{4} .

The operation is as follows:

The desired key slides d^3 being set by the operator cause a setting of the corresponding slides d the projections f thereon coming over the punches it is desired shall operate. The setting of a slide d causes the particular plug 3 associated therewith to be raised, the lever 8 ^{1} to turn upon its pivot, and the rod 10 to be pushed forward, causing the appropriate perforation in the plate 1 to be cov-

110

130

- ered when the punches *c*, being unable to rise, produce the desired perforations in the field key. Upon the release of the key levers and their return to their normal position, the 5 springs 18 return the rods 10-10¹ and 10², and at the same time turn the levers 8^a, which in their turn press upon the tops of the plugs 3 and press them down into a position ready for the next operation.
- 10 In the alternative arrangement already referred to in which the perforations in the field key are indicative of a fact consequent upon any one or more of a series of other facts recorded by the operator, assuming it 15 is desired to take a census of the population of a country and at the same time to ascertain the number of persons qualified to vote, and assuming this census to be made in America, the return would have to be examined to 20 ascertain whether the individual were, for instance, a male twenty-one years of age or over, of native birth or naturalized, not a pauper unless a veteran, and not mentally unfit. Under these circumstances the men- 25 tal operation necessary to determine the qualified from the unqualified would have to be repeated a great number of times, say 110,000,000. By means of the present invention the operator will, in recording the facts 30 appropriate to each individual "is" or "is not" qualified to vote. In this case the operating surfaces on the punch setting slides are so arranged that a consequential setting of the qualifying punch is automatically se- 35 cured. Thus for example assuming the punch controlling slide to have been set to produce a perforation consequent upon the recording by the operator of the facts that the individual is white, naturalized, not a 40 pauper, twenty-one years of age or over. The facts so far recorded are in favor of the individual being qualified to vote. However, if in so setting up data by means of the various slide keys *d*⁵ the operator actuates 45 one of the slides *d* with which one of the rollers 5 is associated, one of the perforations marked "0"—"9" will be covered, through the mechanism heretofore described, and an additional perforation made on the 50 card automatically and unknown to the operator. The numbers "0"—"9" may represent "insanity," "pauperism," "idiot," "citizenship," "veteran" etc. respectively, some of which notations would disqualify the 55 voter and others permit the vote to stand. After the card has been perforated by the voter with the data he desires, and also with data as explained above, unknown to him, the cards may then be passed through any 60 well known sorting machine for perforated records. The sorting machine is first set to analyze "idiot" "pauperism," etc., so that cards having these perforations will be sorted out from those bearing "citizenship," 65 "veteran" etc., and in this way the legal and good votes, separated from the illegal and unqualified votes.
- Claims:
1. In a punching device, the combination of a group of operable punches; a single supplemental punch associated with the group; and means for bringing about the operation of the supplemental punch whenever any one of the punches of the group is operated. 75
2. In a punching device, the combination of a plurality of groups of operable punches; a supplemental punch associated with each group; and means for causing a punch of any group and the associated supplemental 80 punch to be simultaneously operated.
3. In a card-punch, the combination of a plurality of groups of operable punches; a single supplemental punch associated with each group; means for causing the operation 85 of any punch of any group; and means for bringing about the operation of a supplemental punch whenever any punch in its associated group is operated.
4. In a punch for perforating record cards 90 for use in tabulating and sorting machines the combination with slides controlling the operation of a series of punches of a second series of punches controlled by members set by the slides controlling the punches of the first series and by means of which second series of punches perforations are automatically punched whenever a punch in the first series is caused to punch a definite combination of holes. 100
5. In a punch for perforating record cards for use in tabulating and sorting machines the combination with slides controlling the operation of a series of punches of cam surfaces upon the first slides, a second series 105 of slides, means operated by the cam surfaces to actuate said second slides, a second series of punches, and means for retaining said punches in the operative position actuated by the second series of slides. 110
6. In a punch for perforating record cards for use in tabulating and sorting machines the combination with slides controlling the operation of a series of punches, a second series of slides, a support for said slides, 115 perforations in said support, a number of plugs engaging said perforations and adapted to operate the slides, rollers on said plugs, cam surfaces upon the first slides engaging said rollers, a second series of 120 punches, pins resting upon said punches, the operation of the pins and through them that of the second series of punches being controlled by the slides of the second series.
7. In a punch for perforating record cards 125 for use in tabulating and sorting machines the combination with slides controlling the operation of a series of punches, of a second series of slides, a supporting plate for said slides, perforations in said support, a num- 130

ber of plugs engaging said perforations and adapted to operate the slides, bell crank levers pivotally mounted upon the aforesaid plate, a second series of slides also mounted upon said plate and operated by said levers, rollers upon the plugs, cam surfaces upon the slides of the first series engaging said rollers, springs operating the slides of the second series against the levers, a second series of punches and pins resting upon said punches, the operation of the pins and through them the operation of the second series of punches being controlled by the slides of the second series.

15 8. In a punch for perforating record cards for use in tabulating and sorting machines the combination with slides controlling the operation of the punches and means for controlling the operation of a second series of 20 punches controlled by said slides of means whereby the operation of certain of the second series of punches may be controlled by hand.

9. In a punch for perforating record cards for use in tabulating and sorting machines, a main series of groups of punches, a secondary series of single punches, each associated with one of said groups of punches, means for effecting a consequential setting of the 30 second series, said setting means for the secondary series of punches being controlled by the setting of the punches of the first series.

10. In a punch for perforating record cards for use in tabulating and sorting machines, a main series of punches, a secondary series of punches, means for setting the punches of the secondary series controlled by the setting of the punches of the first 40 series, and means whereby the setting of the punches of the secondary series may be altered in consequence of the setting of certain punches of the main series, the effect being that the formation of perforations by 45 the secondary punches is controlled by a

plurality of settings of the punches of the first series.

11. In a punch for perforating record cards for use in tabulating and sorting machines, the combination with a series of 50 punches, slides for controlling their operation, a second series of punches, members for controlling them, said members set by the slides controlling the punches of the first series and by means of said second 55 series of punches perforations are automatically punched whenever a punch in the first series is caused to punch any one of a given number of holes.

12. In a punch for perforating record 60 cards for use in tabulating and sorting machines, the combination with a series of punches, slides for controlling their operation, a second series of punches, reciprocating members for controlling them, said 65 reciprocating members set by the slides controlling the punches of the first series and by means of said second series of punches perforations are automatically punched whenever a punch in the first series is caused 70 to punch any one of a given number of holes.

13. In a punch for perforating record cards for use in tabulating and sorting machines, the combination with a series of punches, members for controlling their op- 75 eration, of a second series of punches, members for controlling them, said members set by the first mentioned members controlling the punches of the first series, and by means of said second series of punches perforations 80 are automatically punched whenever a punch in the first series is caused to punch any one of a given number of holes.

In witness whereof I have hereunto set my hand in the presence of the two under- 85 signed witnesses.

ROBERT NEIL WILLIAMS.
